ADJUSTABLE EAVE GUTTER SUPPORT
OR HANGER

Charles W. Henry, Hennessey, Okla.

Application June 3, 1949, Serial No. 96,861

4 Claims. (Cl. 248—48.1)

1

This invention relates to gutter-hanger devices, and more particularly to a bracket or hanger device for supporting or hanging roof gutters, said device being of the adjustable type.

A main object of the invention is to provide a novel and improved adjustable gutter hanger device which is very simple in construction, very easy to install, and which permits roof gutters to be hung in proper position without requiring nails to be employed through the shingles adjacent the gutter.

A further object of the invention is to provide an improved gutter-supporting bracket or hanger which is very inexpensive to manufacture, neat in appearance, which provides a secure support for the gutter, and which is adjustable to meet a wide range of structural conditions.

Further objects and advantages of the invention will become apparent from the following description and claims, and from the accompanying drawings, wherein:

Figure 1 is a side elevational view of the main body portion of a gutter-supporting device constructed in accordance with the present invention;

Figure 2 is a cross-sectional view taken on line 2—2 of Figure 1;

Figure 3 is a perspective view of a hanger strap employed with the supporting member of Figure 1;

Figure 4 is a cross-sectional view taken through a building adjacent the eave portion thereof, showing a gutter-supporting device in accordance with the present invention installed in operative position;

Figure 5 is a view similar to Figure 4, showing a modified gutter-supporting device of the present invention employed on a building whose roof has a relatively steep slope as compared to the building illustrated in Figure 4;

Figure 6 is a fragmentary view of the end portion of a further modified form of supporting bracket according to the present invention adapted to receive a gutter of different shape from the bracket shown in Figures 1 to 5.

Referring to the drawings, 11 designates the main body portion of the gutter-supporting bracket, said main body portion comprising a strap member 12 of suitable metal bar stock which has secured to its outer end a saddle member 13. Saddle member 13 is curved to correspond with the cross-sectional contour of standard gutters and is adapted to receive a standard gutter therein. The saddle member 13 has an

2

inturned depending lip 14 at its inner end which is adapted to fit over the inside margin of the gutter. At its outer end the saddle member 13 is looped, as shown at 15, to receive the outer marginal bead of the gutter.

The outer portion of strap member 12 adjacent saddle member 13, is downwardly bowed, as shown at 16, and is formed at its bottom edge with a series of square notches 17.

The strap member 12 is pivotally secured at its inner end within a U-bracket 19 having the securing feet 22. As shown in Figure 4, the feet 22 of bracket 19 may be secured adjacent the eave of a building by means of nails 21 passing upwardly through the feet 22 into the under surface of a rafter or associated member 23. Referring to Figure 4, it will be seen that the head 24' of a vertical depending flat T-shaped bar member 24 is fastened to the outer surface of the member 23 adjacent the strap member 12, said bar member 24 being formed at one margin of its depending leg with anchoring means or notches defining a series of vertically-spaced, upwardly-hooked lugs 25. One of the square notches 17 of the member 12 is engaged over a selected hooked lug 25, the notched portion of member 12 being received in the vertical notch portion of the bar 24 inwardly adjacent the selected lug. The cooperating notch 17 and lug 25 are selected so that the saddle 13 will be located in the correct position to receive the gutter whereby the gutter will be positioned to receive drainage from the roof shingles, shown at 26. In the case of a roof having a relatively steep slope, such as is shown in Figure 5 a supporting device is employed of the same general type as in Figure 4, but wherein the downwardly-bowed notched portion, shown at 16' is located in the intermediate portion of the strap member and wherein the end portions of the strap member are at an obtuse angle to each other. The head 24' of the supporting bar 24 is also bent at an obtuse angle to the vertical depending portion of bar 24, as shown at 27, so that said vertical depending portion may interlock with a notch 17 in the bottom edge of the bowed portion 16'. It will be further noted that in Figure 5, the outer end portion of the main strap member is angularly bent with respect to the inner end portion so as to be substantially horizontal, whereby the saddle 13 will support a gutter in the required horizontal position underlying the end shingle of the roof.

As shown in Figure 6, the saddle member, designated at 13', may be formed to receive a gutter

of right-angled cross-sectional contour instead of round contour. The saddle member 13' is provided with a downwardly-bent, inner lug 14 similar to that employed in saddle member 13.

While certain specific embodiments of gutter-supporting brackets have been disclosed in the foregoing description, it will be understood that various modifications within the spirit of the invention may occur to those skilled in the art. Therefore, it is intended that no limitations be placed on the invention except as defined by the scope of the appended claims.

What is claimed is:

1. A device for supporting a gutter contiguous to and spaced outwardly of a projecting eave of a roof comprising a downwardly depending hanger, means extending through the upper end of said hanger for fixedly securing the latter to said eave, a strap disposed contiguous to one side of said hanger and having one end extending beneath said eave and having the other end projecting beyond said eave, means connected to said one end of said strap for pivotally mounting said strap on said eave for rocking movement in a vertical plane along said one side of said hanger, an upwardly opening gutter-supporting saddle disposed in said vertical plane adjacent to said other end of said strap and secured thereto, anchoring means on said hanger, and means provided on said strap engaging said anchoring means for detachably securing said strap at select points along said hanger.

2. A device for supporting a gutter contiguous to and spaced outwardly of a projecting eave of a roof comprising a downwardly depending hanger, means extending through the upper end of said hanger for fixedly securing the latter to said eave, a strap disposed contiguous to one side of said hanger and having one end extending beneath said eave and having the other end projecting beyond said eave, means connected to said one end of said strap for pivotally mounting said strap on said eave for rocking movement in a vertical plane along said one side of said hanger, an upwardly opening gutter-supporting saddle disposed in said vertical plane adjacent to said other end of said strap and secured thereto, anchoring means on said hanger, and means provided on said strap engaging said anchoring means for detachably securing said strap at select points along said hanger, the means provided on said strap comprising a plurality of longitudinally spaced notches provided in the bottom edge of said strap, and the anchoring means on said hanger comprising a plurality of longitudinally spaced upwardly opening hooked lugs adapted to engage the bounding portions of select ones of said notches, the free ends of said saddle being turned inwardly to form lips adapted to fit over the inner and outer margins of the gutter.

3. A device for supporting a gutter contiguous to and spaced outwardly of a projecting eave of a roof comprising a downwardly depending hanger, means extending through the upper end of said hanger for fixedly securing the latter to said eave, a strap disposed contiguous to one side of said hanger and having one end extending beneath said eave and having the other end projecting beyond said eave, means connected to said one end of said strap for pivotally mounting said strap on said eave for rocking movement in a vertical plane along said one side of said hanger, an upwardly opening gutter-supporting saddle disposed in said vertical plane adjacent to said other end of said strap and secured thereto, anchoring means on said hanger, and means provided on said strap engaging said anchoring means for detachably securing said strap at select points along said hanger, the free ends of said saddle being turned inwardly to form lips adapted to fit over the inner and outer margins of the gutter.

4. A device for supporting a gutter contiguous to and spaced outwardly of the projecting eave of a roof comprising a downwardly depending hanger, means extending through the upper end of said hanger for fixedly securing the latter to said eave, a strap disposed contiguous to one side of said hanger and having one end extending beneath said eave and having the other end projecting beyond said eave, means connected to said one end of said strap for pivotally mounting said strap on said eave for rocking movement in a vertical plane along said one side of said hanger, an upwardly opening gutter-supporting saddle disposed in said vertical plane adjacent to said other end of said strap and secured thereto, anchoring means on said hanger, and means provided on said strap engaging said anchoring means for detachably securing said strap at select points along said hanger, the means provided on said strap comprising a plurality of longitudinally spaced notches provided in the bottom edge of said strap, and the anchoring means on said hanger comprising a plurality of longitudinally spaced upwardly opening hooked lugs adapted to engage the bounding portions of select ones of said notches, the free ends of said saddle being turned inwardly to form lips adapted to fit over the inner and outer margins of the gutter.
